UNITED STATES PATENT OFFICE

OLOF SÖDERLUND AND THOMAS GRAM, OF LONDON, ENGLAND, ASSIGNORS TO TECHNO-CHEMICAL LABORATORIES, LIMITED, OF LONDON, ENGLAND

DRYING OF MOIST MATERIAL

Original application filed October 3, 1927, Serial No. 223,750, and in Great Britain October 7, 1926. Divided and this application filed October 11, 1929. Serial No. 399,013.

This application is a continuation in part of our applications Serial No. 223,750 filed 3d October, 1927, and Serial No. 272,264, filed 23d April, 1928.

5. This invention relates to the drying of materials while suspended in and carried by a gaseous medium adjacent to heated surfaces.

In such arrangements it has been proposed to blow air through one or more tubes 10 which are situated in the region of a furnace and its adjacent flues or passages for the products of combustion, while disintegrated material which is to be dried is fed 15 into the stream of air at the highest temperature region, the whole passing therefrom into a drying chamber.

The object of the present invention is to provide for the drying of certain substances 20 such as coal dust, peat, lignite, brewers' grain, grass or fodder crops or other materials having small particles or particles with at least one small dimension at a reasonable speed and by the use of comparatively small quantities of heat at a moderate 25 temperature.

The present invention consists in a method of drying material while carried in suspension by a gaseous medium through one 30 or more conduits having heated walls according to which the carrying medium fully charged with the material is spread laterally to extended form preferably while moving in an upward direction to secure uniform distribution of the material in the medium during the major part of the drying 35 operation.

The invention further consists in a method 40 according to the preceding paragraph in which spreading is effected as by changing the conduit section from one large passage to a plurality of small tubes or passages of other form presenting large wall contour in relation to cross-sectional area 45 in order to bring all the material into close proximity to the heated conduit walls.

The invention further consists in a method 50 according to one or both of the preceding paragraphs which is carried out in a drying conduit comprising a bank or plurality

of long tubes or one or more flat narrow conduits of considerable length disposed in a tortuous and preferably up-and-down direction.

The invention further consists in a method 55 in accordance with any of the preceding paragraphs in which a liquid and/or the substantially saturated vapour thereof as for example water and steam are employed to heat the walls of the drying conduits.

The invention also consists in improvements in the drying of moist material 60 as hereinafter described.

Figure 1 shows apparatus for operating in accordance with the invention, the drawing representing only the two ends of the apparatus which will be of any desirable length for performing the necessary functions;

Figure 2 is a plan view showing the heating vessel and arrangement of tubes therein. 70

In the apparatus for carrying the method into effect illustrated by way of example a cylindrical chamber α is fitted with tube plates a^3, a^4 at the top and bottom and filled 75 with groups of vertical tubes which are of small diameter in order that none of the material may be far from the surrounding heated wall of the drying conduit and a large contour of wall surface may be presented for a given total cross-sectional area 80 of conduit. Of the six groups b, b', b^2, b^3, b^4 and b^5 the combined cross section of any two similar groups constitute the area of the drying conduit and the groups are connected 85 to one another by the common headers d^2, d^3 at the bottom and by individual return bends d^4, d^5 at the top.

The conduit g is fitted with a charging device e having a hopper e^2 and a distributor e' for introducing the material of the kind indicated and which may be disintegrated into the carrying medium and the bend d forms the inlet to the large wall surface drying conduit formed by the tube groups. The outlet d' from the last two groups is taken to the inlet f^2 of the cyclone f which is provided with the discharge f' at the bottom for the dried material.

The outlet f^3 from the cyclone is connected 100

to the inlet c' of the fan c which draws the material-laden gaseous carrying medium through the various tube groups of the drying conduit and after separation of the solid material in the cyclone delivers the carrying medium charged with vapour but freed from material to a main g' which may conduct it to any desired locality where it may be suitably disposed of.

10 Heat is supplied to the tubes by means of a heating fluid, for instance hot water or condensing steam, which is admitted by the pipe a' and flows inside the chamber a between the tubes while the condensate leaves 15 by the pipe a^2 . Steam previously put to other uses forms an economical heating medium which is particularly suited for operating in accordance with the present method and the heating of the drying conduit is 20 substantially uniform and is as shown carried as near as practicable to the point where the material is separated from the carrying medium to prevent condensation of the vapour permeating the medium on the material 25 as according to the invention the carrying medium only transmits heat the very short distance from the walls to the material which is all closely adjacent thereto and there is practically no storing of heat in the 30 carrying medium to be imparted to material which it may subsequently meet.

A carrying medium such as air is drawn into the apparatus through the pipe g , the quantity being controlled by a damper (not 35 shown) at any convenient position and the velocity being sufficient to carry the material which is to be dried. The material in regulated proportion to the air is added at the charging device e .

40 The air and material are so proportioned that the air carries the maximum amount of material possible for its velocity and upon entering the drier from the bend d the material-laden air is spread out so as to contact 45 with an extended contour of wall surface for example as shown by being divided up into a large number of small diameter tubes.

The spreading laterally of the material-laden air from compact to attenuated, dispersed, separated or other extended cross-sectional form takes place at the bottoms of the extended contour regions or lengths of tubes and this is essential to ensure uniform distribution which is thus accomplished 55 owing to the fact that if the material tends to collect together to a greater extent in one section than another of the total conduit area the velocity of the air will be checked in this section and, therefore, more air will tend to 60 pass through other sections with the result that a greater amount of material will be carried to the other sections and uniformity of distribution will be automatically maintained.

65 The material-laden air passes by way of

the plurality of tubes forming the total area of the drying conduit and at the top one set of tubes b is returned in one direction and the other set of tubes b^2 in the other direction, each tube being here provided with an individual bend so that all the material that passes up a tube must return down the continuation of the same tube and no variation of the distribution can occur due to the downward movement.

70 At the bottoms of the tubes b' , b^4 all of the material-laden air enters a common return bend d^2 or d^3 and when returning in the upward direction the material-laden air is again spread out or divided into a plurality 80 of small tubes at the bottoms of the groups b^2 and b^5 . The tube groups will be of considerable length, portions only at each end being shown in the drawing.

75 In Figure 2 the arrangement of the groups of tubes is indicated but the employment of a plurality of tubes is not essential and each row or line of tubes may be replaced by a narrow conduit of a width corresponding with the length of the row, 85 the conduit being divided into parallel compartments by ribs or divisions if desired. Any other arrangement adapted to provide a considerable length of wall contour or perimeter in relation to the cross-sectional 95 area of the drying conduit or passage may also be employed if desired.

80 In the event of the design leading to an inconvenient length of the tubes or to the gases having to flow upwards and downwards an excessive number of times, the flow may be modified so that the gases, after passing through one upward and downward group of tubes, are again directed by a fan 90 through the same group by suitable pipes 100 and return bends.

85 The apparatus illustrated provides a substantially uniform wall temperature throughout the drying conduit and heating medium of an inexpensive nature is conveniently employed therein. The wall temperature may, however, be progressively increased along the conduit with advantage 110 as by counterflow if convenient.

Having now described our invention, 115 what we claim as new and desire to secure by Letters Patent is:—

1. The method of evaporating moisture from divided material comprising charging material in particles having at least one 120 small dimension into a compact moving stream of gaseous carrying medium, increasing the length of the wall perimeter of the cross section of said stream without substantially altering the cross-sectional area 125 thereof, conducting said stream a considerable distance along said increased perimeter region while heating the walls thereof and finally separating the material from the 130 stream of medium.

2. The method of evaporating moisture from divided material comprising charging material in particles having at least one small dimension into a compact moving stream of air, upwardly directing and attenuating said stream without substantially altering the cross-sectional area thereof, conducting said stream a considerable distance in an attenuated condition while heating the containing walls and finally separating the material from the stream.

3. The method of evaporating moisture from divided material comprising charging material in particles into a compact moving stream of gaseous carrying medium, dividing said stream into a plurality of smaller streams, conducting said plurality of small streams a considerable distance while heating the walls confining the same, reuniting said small streams and finally separating the material from the stream of medium.

4. The method of evaporating moisture from divided material comprising charging material in particles into a compact moving stream of air, dividing said stream into a plurality of smaller streams while upwardly directing the same, conducting said plurality of small streams a considerable distance while heating the walls confining the same, reuniting said small streams and finally separating the material from the stream.

5. The method of evaporating moisture from divided material comprising charging material in particles into a compact moving stream of gaseous carrying medium, dividing said stream into a plurality of smaller streams while upwardly directing the same, conducting said plurality of small streams a considerable distance in an upward and downward direction while moderately heating the walls confining the same, reuniting said small streams and finally separating the material from the stream of medium.

45 6. The method of evaporating moisture from divided material comprising charging material in particles into a compact moving stream of air, dividing said stream into a plurality of smaller streams while upwardly directing the same, conducting said plurality of small streams a considerable distance in an upward and downward direction while heating the walls confining the same with hot water or the vapour thereof, reuniting said small streams and finally separating the material from the stream.

7. The method of rapidly drying divided material at comparatively low temperatures comprising charging material in particles having at least one small dimension into a compact moving stream of gaseous carrying medium, increasing the length of the wall perimeter of the cross section of said stream without substantially altering the cross-sectional area thereof while upwardly direct-

ing said charged stream, conducting said stream a considerable distance upward and then downward in regions of similar perimeter, altering the increased perimeter conditions and reinstating them while the stream is again directed upwards, heating the walls of all the increased perimeter regions with hot aqueous material and finally separating the material from the stream of medium.

8. The method of rapidly drying divided material at comparatively low temperatures comprising charging material in particles having at least one small dimension into a compact moving stream of gaseous carrying medium, dividing said stream into a plurality of smaller streams while upwardly directing the same, conducting said plurality of small streams a considerable distance upwards and then downwards without substantial alteration of cross section, reuniting a number of said streams and again separating them while moving upwards, heating the walls confining the small streams with hot aqueous material, reuniting said small streams and finally separating the material from the stream of medium.

In testimony whereof we have signed our names to this specification.
